NEWSPAPER DELIVERY TUBE WITH ONE BOLT MOUNTING

BACKGROUND OF THE INVENTION

1. Field of the Invention

This invention relates to newspaper delivery or motor route tubes of the type normally used by newspapers for facilitating delivery of newspapers along rural roads and the like.

2. Description of the Prior Art

Prior structures of this type comprise various-shaped tubes which have been mounted on angle brackets by conventional fastener means so as to enable the tubes to be supported on the stakes or posts.

The prior art mounting devices require the use of a plurality of fasteners such as nut and bolt assemblies which, in turn required the presence of several apertures in the bottom of the tube to permit installation of the nut-bolt assemblies. The presence of the openings frequently weakened this portion of the tube particularly when the same is molded of plastic as is becoming common in the art with the result that breakage commonly occurred. By molding a combination fastener and mounting means requiring only one bolt, the area of the tube is reinforced and accidental fracture is prevented. Additionally and of considerable importance is the fact that the necessary angle bracket for mounting the tube can be affixed to the tube in a very short time with complete accuracy due to the molded configurations formed in the tube itself which engage the angle bracket and largely secure the tube thereto.

SUMMARY OF THE INVENTION

A newspaper delivery or motor route tube having one exterior surface thereof formed with a configuration for registry and engagement with an angle bracket to be secure thereto by means of which the motor route tube is mounted on a post or stake. The configuration includes guide members for positioning and locating the bracket and projecting peg like members engaging apertures in the brackets to secure the same thereto.

DESCRIPTION OF THE DRAWINGS

FIG. 1 is an exploded perspective view of the newspaper delivery or motor route tube and the L-shaped mounting bracket to be attached thereto.

FIG. 2 is a bottom plan view on line 2-2 of FIG. 1.

FIG. 3 is a horizontal section on line 3-3 of FIG. 2.

DESCRIPTION OF THE PREFERRED EMBODIMENT

By referring to the drawings and FIG. 1 in particular, a motor route tube or newspaper delivery tube may be seen in position on its side with respect to its normal upright position in use. The motor route tube comprises a cross-sectionally rectangular tubular member 10 having an open end 11 and a closed end 12. The normal bottom portion of the motor route tube 10 is generally indicated by the numeral 13 and includes drainage apertures 14 and a centrally disposed ribbed portion 15 through which a central aperture 16 extends. A plurality of cross-sectionally circular projecting members 17 are integrally formed with a ribbed portion 15 and the bottom 13 of the route tube and these preferably are hollow throughout a portion of their extending length so as to impart a degree of resiliency thereto. Spaced parallel guides 18 are formed on either side of the ribbed portion 15 and they are also spaced with respect to the plurality of projecting members 17 heretofore referred to. Each of the spaced parallel guides is provided with a plurality of integrally formed abutments 19.

Still referring to FIG. 1 of the drawings, it will be seen that an L-shaped mounting bracket generally indicated by the numeral 20 is disclosed and that it includes flanges 21 on its longitudinal edges and that one portion thereof has a plurality of openings 22 located for registry over the projecting members 17 on the route tube. A central opening 23 registers with the central opening 16 in the ribbed portion 15 and provides for the positioning of a nut and bolt assembly which secures the

mounting bracket 20 to the route tube by maintaining the relative position of the mounting bracket 20 on the projecting member 17 and between the spaced parallel guides 18. The other portion of the mounting bracket 20 has slots and circular openings 24 therein so that fasteners such as U-bolts can be positioned there through and engage a stake or metal post so that the bracket can be secured thereto as necessary in holding the motor route tube in elevated position alongside a roadway where it will serve as a desirable receptacle for a newspaper.

By referring to FIG. 2 of the drawings which is a bottom plan view of the motor route tube, it will be observed that the opening comprising the one end 11 is tapered so that the top portion of the tube is longer than the bottom portion 13 and this provides a weather cover as is customary in some motor route tubes.

In FIG. 3 of the drawings, the cross-sectional elevation through the motor route tube shows integral molded construction of the tube including the bottom portion 11, the ribbed portion 15, the projecting members 17 and the side guides 18 and it will be obvious that the projecting members 15 extend sufficiently with respect to the ribbed portion 15 that they engage and extend through the openings 22 in the L-shaped mounting bracket so that they and the spaced parallel guides 18 rigidly hold the mounting bracket in position on the tube. The addition of a nut and bolt assembly through the registering opening 16 and 23 merely serves to hold the assembly in position and prevent accidental disengagement.

It will be seen that the configuration of the bottom portion 13 of the route tube 10 is such that the added material and the arrangement thereof suitably reinforces this bottom portion so that the side guides 18 form transversely extending ribs when the tube is in its normal upright position as well as defining guides and abutments for the sides of the L-shaped bracket 20 and the ribbed portion 15 strengthens the bottom of the tube 13 and provides for ventilation which prevents water collecting between the L-shaped bracket which is usually plated steel and the tube and thereby prevents rust or deterioration of the bracket itself.

In FIG. 3 of the drawings, the bottom portion 13 of the route tube 10 will be seen to have a longitudinal raised rib 24 therein. This is one of a pair of such ribs that are formed in the bottom of the tube to support a newspaper in elevated relation to the actual inner bottom surface to prevent water damage and these ribs automatically provide clearance between the newspaper positioned in the tube and the head of a nut and bolt assembly positioned through the registering openings 16 and 23 as heretofore referred to.

The above described structure provides relatively easy and fast attachment of the L-shaped mounting bracket 20 to the motor route tube and insures the accurate and dependable positioning of the L-shaped bracket relative thereto. The bracket itself is then attached to a supporting metal fence post or stake as common in the art by means such as U-bolt (not shown) and the construction thus considerably expedites the installation of a motor route tube and at the same time results in a structurally improved motor route tube construction.

Although but one embodiment of the present invention has been illustrated and described, it will be apparent to those skilled in the art that various changes and modifications may be made therein without departing from the spirit of the invention or from the scope of the appended claims.

We claim:

1. A newspaper delivery tube for the deposit of newspapers and the like having integral reinforcing and mounting means, comprising:
  - a. a tubular elongate body;
  - b. integral reinforcing and mounting means on an outer surface of said tubular body, said reinforcing and mounting means including a pair of spaced guide flanges integral with said tubular body and extending from said surface for reinforcing said body, a plurality of pins integral with said body and projecting from said surface between said

flanges, a bolt-receiving opening in said body through said surface between said flanges, bracket means cooperating with said mounting means, said bracket means having opposite side edges closely received between said spaced flanges and a plurality of openings therethrough in which are received said pins to securely hold said bracket to said body in a predetermined orientation, and a bolt receiving opening through said bracket means in alignment with said bolt receiving opening

10

through said body for receiving a bolt extended through said bracket and said body so that said body and bracket may be quickly and easily secured together in a rigid and accurate manner with only one bolt.

5 2. A newspaper delivery tube as in claim 1, wherein said flanges extend from said body at right angles and abutments are provided between said flanges and said surface on the opposite side of said flanges from said pins.
